UNITED STATES PATENT OFFICE.

GEORGE L. SWIFT, OF CHICAGO, ILLINOIS.

FINE-FUEL-FEEDING APPARATUS.

984,715.

Specification of Letters Patent. Patented Feb. 21, 1911.

Application filed March 14, 1907. Serial No. 362,254.

To all whom it may concern:

Be it known that I, GEORGE L. SWIFT, a citizen of the United States, residing at Chicago, in the county of Cook and State of Illinois, have invented certain new and useful Improvements in Fine-Fuel-Feeding Apparatus, of which the following is a full, clear, and exact specification.

This invention relates to improvements in fine fuel feeding apparatus, and the primary object of the invention is to provide an improved device of this character which will intermittently feed a small quantity of fuel.

A further object is to provide an improved device of this character, which will alternately discharge the fuel first to one side and then to the other to equally distribute the same to the fire.

A further object is to provide an improved device of this character, which will be simple and efficient, and which may be adjusted to regulate the feed of the fuel.

To the attainment of these ends and the accomplishment of other new and useful objects, as will appear, the invention consists in the features of novelty in the construction, combination and arrangement of the various features hereinafter more fully described and claimed, and shown in the accompanying drawings illustrating an exemplification of the invention, and in which:—

Figure 1 is a side elevation of the machine constructed in accordance with the principles of this invention; Fig. 2 is a longitudinal sectional view of Fig. 1; Fig. 3 is a front elevation of Fig. 1; Fig. 4 is a detail elevation of one of the distributing blades; Fig. 5 is a view looking at the lower edge of Fig. 4; Fig. 6 is a detail sectional view on line 40 6—6 of Fig. 2.

Referring more particularly to the drawings, and in which the same reference numerals designate similar parts throughout the several views, the numeral 10 designates a suitable hopper in which the fuel is placed. This hopper is preferably provided with a delivery opening, and an inclined bottom 11, which latter projects slightly beyond the delivery opening, and terminates in a corrugated front edge, as at 12, which extends into the induction door or opening in the furnace when the hopper is supported in position.

Secured to the sides of the hopper, preferably on suitable projections or bosses 13, and by one end, are arms or brackets 14. These

arms or brackets are preferably located adjacent the lower extremity of the hopper, and project beyond the delivery opening, and journaled in these arms or brackets, and across the opening in the hopper, is a shaft 15, secured to the ends of which, and preferably adjacent the inner faces of the side walls of the hopper, are disks or heads which extend into the hopper. Pivots supported by and between the disks or heads 16, adjacent the peripheries thereof and arranged parallel with each other and the shaft 15, are members 17, secured to which, in any suitable manner, are blades or members 18. The body portions of these blades or members 18 are provided with apertures or perforations 18^a and their lower edges are split as at 18^b to form a series of wings 18^c throughout their length. The ends or sides of these wings are bent or deflected so as to twist the portion of the blades or members between the notches to the position as shown more clearly in Fig. 5 of the drawings, to extend transversely of the body portion 18 and in an oblique position to form spaced parallel wings; the wings on each alternate blade being disposed in the opposite direction, as shown more clearly in Fig. 2 of the drawing, for a purpose to be set forth. By pivots mounting the blades upon their supports, it will be apparent that they will yield sufficiently, should they strike any hard substance in the coal, to permit the edges of the blades to pass over such substance, and after passing, the centrifugal force will cause the blades to assume a proper position with respect to the other blades. As the shaft and heads 16 rotate, the centrifugal motion will cause the free ends of the blades or members to assume a position in a direct line with their point of pivotal support and the shaft 15, so that the winged edge will engage and scrape against the bottom 11. Obviously the members 17 and the wings or blades 18 may be formed integral if desired.

Within the hopper, and just above the point of the extreme movement of the blades or members 18, is a fuel support 19, which extends across the hopper and is spaced from the bottom 11, so as to permit the fuel to pass between the edge thereof and the base 11, and into position to be engaged by the blades or members 18, in a manner to be set forth. Pivots supported within the hopper, preferably by the side walls thereof and

adjacent the discharge or delivery opening, is an agitator plate 20. This plate is preferably pivoted adjacent the rear side of the hopper, and extends from a point 5 above, and downwardly in an inclined direction from said point toward and terminating short of the support 19.

A deflector or regulating plate 21 is preferably pivotally supported by the side walls 10 of the hopper at a point near the top and adjacent the front of the hopper, and this plate extends downwardly toward the support 19.

An arm or lever 22 is pivotally supported on the outside of one of the side walls of the 15 hopper by one end, as at 23, and is provided with a slotted portion 24, through which a suitable headed screw or bolt 25 passes and engages the wall of the hopper. This arm or lever is adapted to be moved 20 about its pivot 23 and clamped or held in its adjusted position by means of the screw or bolt 25, as will be understood.

Removably clamped or secured to the pivot 26 of the agitator plate 20, adjacent the 25 outer face of the side of the hopper to which the arm or lever 22 is pivoted, is one end of a bar or member 27, the free end of which preferably extends or projects beyond the front wall of the hopper and engages and 30 rests upon a laterally projecting lug or pin 28 on the arm or lever 22. A similar bar or member 29 is clamped or secured to the pivot 30 of the deflector plate 21, the free end of which extends toward and rests upon the 35 bar or member 27, preferably at a point intermediate the point of its engagement with the pivot 26 of the agitator plate and the lug 28 on the arm or lever 22. If desired, a suitable anti-friction roller 31 may be mounted 40 upon the extremity of the bar or member 29 to reduce the friction at this point. Thus it will be seen that when the lever or arm 45 22 is clamped in position so that the end of the bar or member 27 rests upon the lug or projection 28, the plates 20-21 will be directed toward each other and held in position, with the opening between the free extremities, at a point above the support 19, so that when anything fine is placed in the 50 hopper, these plates will direct the same through the space between them and on to the support 19. This opening may be varied by loosening the nut or bolt 25 and moving the arm or lever 22 about its pivot 23, the lug 55 or pin 28 thus raising or lowering the bar or member 27 to rock the plate 20, and said bar or member 27 will rock the plate 21 through the medium of the engaging bar or member 29. When the plates 20 and 21 60 have assumed the desired relative position, they may be retained in such position by tightening the bolt or screw 25.

Mounted upon a suitable journal 32 on the same side of the hopper is a belt wheel 65 or pulley 33, which is preferably located be-

yond the lever or arm 22 and the bars or members 27-29; and projecting from the inner side of this wheel or pulley 33 is a pin or lateral extension 34. This pin or extension is of such a length and is so located 70 that when the wheel or pulley 33 is rotated, it will engage the bar or member 27 and raise the end thereof off of the lug or projection 28, to simultaneously rock the plates 20-21 about their respective pivots toward each other, and as it passes out of engagement with the bar or member 27, the latter will again drop upon the pin or projection 28 to permit the free ends of the plates to move away from each other. The movements of 75 these plates depend upon the rapidity of rotation of the pulley or wheel 33.

Secured to the extremity of the shaft 15, preferably adjacent the pulley or wheel 33, is a belt pulley 35. The pulley or wheel 33 and the shaft 15 are simultaneously rotated in any suitable manner, such as by means of a driving belt 36, which passes around the pulley 35 and engages the pulley or wheel 33. If desired, the portion 37 of the front 80 of the hopper may be pivotally supported by its upper end, as at 38, in order that access may be had to the hopper through the front.

In operation, the plates 20-21 are adjusted with respect to each other by means of the handle or lever 22, in the manner set forth, and the pulleys 33-35 rotated by the belt 36. The fuel is placed in the hopper and upon the plates 20-21 in any desired manner. As the pulley 33 rotates, the pin or projection 34 engages the bar or member 27, causing the latter to be raised and lowered. This movement will cause the plates to vibrate, moving toward and away 95 from each other. The plate 20 serves as an agitator to force the fuel which drops through the opening between the plates and on to the support, off of the support and against the inclined bottom 11 of the hopper, from where it passes into a position 100 to be engaged by the blades or members 18. These blades or members will drag or shove the fuel forward until it reaches the projecting corrugated end 12 of the bottom of 105 the hopper. The blades or members being pivotally mounted by one edge, will be thrown out by centrifugal motion, and as the free end comes in contact with the fuel, the centrifugal motion will be slightly overcome, causing the blades to turn about their 110 pivot as the material passes between the corrugated end 12 and the shaft 15, but as it reaches the extremity of the end 12, the blade will be thrown out by the centrifugal 115 motion just as the fuel is about to fall, and will toss or throw the fuel onto the fire, instead of scraping it off of the bottom of the hopper and allowing it to drop directly upon the fire. When the apparatus is in 120 125 130

operation the curved bottom 11, of the hopper is fixed in unyielding relation with respect to the sweep of the blades and consequently does not yield under the pressure of the blades, the advantage of this arrangement is that the feeding action on the fuel is accomplished by the full centrifugal force of the revolving blades and is dependent upon the speed of rotation, while at the same time a clear path of movement for the revolving blades is provided which is concentric with the axis of their revolution. This in practice is found to be a most advantageous feature and secures a most efficient fuel feeding action. The perforations 18^a in the blades or members 18 serve to prevent a suction upon the fire during their centrifugal motion. The fuel which passes off of the concaved portion of the end of the hopper bottom will be thrown into the furnace in a plane lower than the portion which is carried farther forward, and thrown from the convex portion, thereby preventing the fuel from being thrown upon the fire at the same place and more evenly distributing the fuel. The deflected portion or wings 18^c on one of the blades or members 18 will throw or deflect the fuel laterally toward the sides of the furnace, and as the wings 30 on the alternate blades are disposed in opposite directions, the fuel will be alternately deflected first to one side and then to the other. These wings coöperating with the corrugated end 12 serve to uniformly distribute the fuel over the entire fire, which will prevent a great accumulation at any one point. When desired, the machine may be readily changed from a right to a left-hand machine, by placing the bars or members 27—29 on the other ends of the pivots of their respective plates 20—21, and providing suitable journals or supports 40—41 respectively, for the handle or lever 22 and the pulley 33.

An improved machine of this character may be so constructed as to accommodate the same to the different sizes of grates, that is, the distance to which the fuel must be thrown varies according to the different size grates, and this may be accomplished by varying the position of the front edge 12 of the bottom 11. The higher the edge 12 is located with relation to the shaft 15, the farther the fuel will be thrown onto the grate. The distance the fuel is thrown may also be regulated by the speed of rotation of the blades or members 18.

In order that the invention might be fully understood by those skilled in the art, the details of the foregoing embodiment thereof have been thus specifically described, but

What I claim as new and desire to secure by Letters-Patent is:—

1. A device of the class described, containing a fuel hopper having a delivery

opening, plates pivotally supported within the hopper, a member operatively related to each of the plates for moving said plates, one of the members engaging the other member intermediate the ends of the latter, and means adapted to engage one of said members beyond the point of engagement of the other member therewith for moving both of the members to simultaneously oscillate the plates.

2. A device of the class described containing a hopper for the fuel, having a delivery opening, plates pivotally supported within the hopper, operative connections between the plates, means adapted to intermittently engage one of the connections for moving the other connection to simultaneously oscillate the plates, and means for limiting the movement of the plates in one direction.

3. A device of the class described containing a hopper for the fuel, having a delivery opening, plates pivotally supported within the hopper, operative connections between the plates, means adapted to intermittently engage one of the connections for moving the other connection to simultaneously oscillate the plates, and means for adjusting said plates with relation to each other.

4. A device of the class described containing a hopper for the fuel, having a delivery opening, plates pivotally supported within the hopper, operative connections between the plates, means adapted to intermittently engage one of the connections for moving the other connection to simultaneously oscillate the plates, and an adjustable stop adapted to be engaged by one of the connections for varying the position of the plates with relation to each other and to limit the movement of the plates in one direction.

5. In a device of the class described, the combination of a hopper for containing the fuel, having a discharge opening, plates pivotally supported within the hopper, an arm connected to one of the plates outside of the hopper, an adjustable stop for supporting the free end of the arm, an arm connected to the other plate, the free end of said arm having a sliding contact with the first said arm, and means adapted to intermittently engage and move the first arm for simultaneously oscillating both of the plates about their pivots to feed the material to the discharge opening.

6. In a device of the class described, the combination of a hopper for containing the fuel, having a discharge opening, plates pivotally supported within the hopper, an arm connected to one of the plates outside of the hopper, an adjustable stop for supporting the free end of the arm, an arm connected to the other plate, the free end of said arm

having a sliding contact with the first said arm, a rotary member supported by the hopper, and a projection on said member adapted to intermittently engage and move the 5 first arm when said member is rotated, for simultaneously moving both arms to oscillate both of said plates about their pivots.

7. In a device of the class described, the combination of a hopper for containing the 10 fuel, having a discharge opening, plates pivotally supported within the hopper and inclined toward each other, a handle or lever adjustably supported by the hopper, a bar or member connected to one of the plates, 15 a projection on the handle or lever adapted to be engaged by the free end of the bar or member for supporting the latter, a bar or member connected to the other plate, the free end thereof having a sliding connection 20 with and being supported by the first bar or member, means for securing the handle or lever in its adjusted position for varying the position of the plates with relation to each other, a rotating member supported by 25 the hopper, and a projection on said rotating member adapted to engage and raise the first bar or member to move the second bar or member for simultaneously oscillating the plates about their pivots.

30. 8. In a device of the class described, the combination of a hopper for containing the fuel, having a discharge opening, pivoted plates within the hopper and inclined toward each other, a fuel support disposed between the ends of the plates adjacent the opening therebetween and the discharge opening of the hopper, means for simultaneously oscillating the plates for delivering the fuel to the support and feeding the same 40 to the discharge opening, and means for forcing the fuel through the discharge opening.

9. In a device of the class described, the combination of a hopper for containing the 45 fuel, having a discharge opening, pivoted plates within the hopper and inclined toward each other, a fuel support disposed between the ends of the plates adjacent the opening therebetween and the discharge opening of the hopper, a member operatively related to each blade, one of the members engaging the other intermediate the ends of the latter, means adapted to engage the said other member for simultaneously 50 oscillating the plates for delivering the fuel to the support and feeding the same to the discharge opening, means for forcing the fuel through the discharge opening, said hopper being provided with an opening adjacent the support, and a closure for the 55 opening.

60. 10. A device of the class described containing a hopper for the fuel, said hopper having a delivery opening, a member arranged within the hopper to revolve, and lo-

cated adjacent the delivery opening, a plurality of blades pivotally supported upon said revoluble member, a bottom for the hopper, said bottom during the operation of the apparatus being fixed in unyielding relation to the path of the blades and having a curved portion substantially concentric with the path of the outer portions of the blades, and terminating in a horizontal delivery edge past which the blades operate, and means for revolving said blade supporting member.

11. In a device of the class described, a hopper having a horizontally extending discharge opening, a distributor shaft journaled in the hopper and in parallel relation with respect to said opening, a plurality of fuel distributor blades pivotally supported by said shaft, said hopper having a bottom portion in unyielding relation and curved to 80 substantially concentric relation with respect to the path of the outer surface of the distributor blades and terminating in an upturned horizontal edge forming the delivery edge of the hopper, over and from which the 85 blades discharge the fuel directly into the furnace, means for feeding the fuel to the hopper and means for rotating said distributor shaft.

12. In a device of the class described, a 90 hopper having a horizontally extending discharge opening, and a fixed unyielding curved bottom portion terminating in an upturned horizontal edge, a plurality of centrifugally-operated pivotally mounted distributor blades, arranged in said hopper and co-operating with said curved bottom and horizontal edge to engage the fuel and discharge the same over and from said edge directly into the furnace chamber, and means 95 for operating said distributor blades.

13. In a device of the class described, a 100 hopper having a discharge opening and a bottom portion terminating in a horizontal edge forming the delivery edge of the hopper discharge opening, said horizontal edge being transversely corrugated, means for feeding the fuel to the opening, a plurality of rotatable pivotally-supported blades arranged within the discharge opening and co-operating with the corrugated delivery edge thereof to discharge the fuel directly 105 into the furnace, and means for rotating said blades.

14. In a device of the class described, a 110 hopper having a horizontally extending discharge opening, and a bottom portion terminating in an unyielding horizontal edge said edge forming the delivery edge of said opening, a rotatable member arranged in 115 the hopper and associated with said opening, a plurality of distributor blades pivotally mounted on said rotatable member, the peripheral surfaces of said blades co-operating with said edge to discharge the fuel there- 120

from directly into the furnace, and means for rotating said rotatable member, the edge of said bottom portion being shaped to cause the fuel to be discharged from said edge in 5 different horizontal planes.

15. In a device of the class described, a hopper having a discharge opening and a bottom portion terminating in a horizontal edge to form the delivery edge of said opening, a rotatable member arranged in the hopper and in parallel relation to said edge, a plurality of distributor blades pivotally mounted on said rotatable member and co-operating with said bottom portion and edge to discharge the fuel from said edge directly into the furnace, said bottom portion being unyielding and curved to concentric relation adjacent said delivery edge, with respect to the path of said distributor 10 blades, and means for rotating said rotatable member.

16. In a device of the class described, a hopper having a discharge opening and a bottom portion terminating in a horizontal edge to form the delivery edge of said opening, a rotatable member arranged in the hopper and in parallel relation to said edge, a plurality of distributor blades pivotally mounted on said rotatable member and co-operating with said bottom portion and edge to discharge the fuel from said edge directly into the furnace, said bottom portion being unyielding and curved to concentric relation, adjacent said delivery edge, with respect to the path of said distributor blades, said blades being disposed with respect to each other to deliver the fuel in diverging directions, and means for rotating said rotatable member.

40 17. In a device of the class described, a hopper having a discharge opening and a bottom portion terminating in a horizontal edge to form the delivery edge of said opening, a rotatable member arranged in the hopper and in parallel relation to said edge, a plurality of distributor blades pivotally mounted on said rotatable member and co-operating with said bottom portion and edge to discharge the fuel therefrom directly into 45 the furnace, said bottom portion being unyielding and curved to concentric relation, adjacent said delivery edge, with respect to the path of said distributor blades, said blades being disposed with respect to each other to deliver the fuel in diverging directions, and means for rotating said rotatable member, the edge of said bottom portion being shaped to discharge the fuel in different horizontal planes.

60 18. In a device of the class described, a hopper having a discharge opening and a fixed unyielding bottom portion terminating in a horizontal edge to form the delivery edge of said opening a rotatable member arranged in the hopper in parallel relation to

said edge, a plurality of distributor blades pivotally mounted on said rotatable member, said blades formed at their outer ends with wings disposed in transverse relation with respect to the body thereof, said unyielding 70 bottom portion being curved to concentric relation with respect to the path of said blades, and means for rotating said rotatable member.

19. In a fuel feeding apparatus, a hopper 75 for the fuel, said hopper having a delivery opening, a member arranged within the hopper to revolve, and located adjacent the delivery opening, a plurality of fuel discharge arms or blades pivotally supported upon 80 said revoluble member, a bottom for the hopper, said bottom being located below the revoluble member and having a curved portion substantially concentric with the path of the peripheries of the fuel discharging 85 arms or blades and terminating in a horizontal delivery edge past which the peripheries of the arms or blades operate, and means for revolving said arm or blade supporting member. 90

20. A device of the class described containing a hopper having a delivery opening, means for feeding the fuel to the opening, a plurality of rotatable blades pivotally-supported by one edge and within the opening 95 for forcing the fuel therethrough, and means for rotating the blades, the free edge of each of the blades being split and twisted to form spaced wings transversely disposed with relation to the body portion for deflecting the 100 fuel.

21. A device of the class described containing a hopper having a delivery opening, means for feeding the fuel to the opening, a plurality of rotatable pivotally-supported 105 blades within the opening for forcing the fuel therethrough, and means for rotating the blades, the free edge of the blades being split and twisted to form spaced wings transversely disposed with relation to the body 110 portion, the wings on each alternate blade being disposed in an opposite direction and adapted to pass over the edge of the bottom of the hopper.

22. A device of the class described containing a hopper for the fuel having a delivery opening, means for feeding the fuel to the opening, a plurality of rotatable blades pivotally-supported by one edge and within the opening for forcing the fuel 115 therethrough, and means for rotating the blades, the free edge of each of the blades being split and the portions of the edge between the splits being deflected beyond both faces thereof to form a plurality of spaced 120 parallel wings extending in an oblique direction with relation to and across the body of the blade and adapted to pass over the edge of the bottom of the hopper to deflect 125 the fuel. 130

23. A device of the class described containing a hopper for the fuel having a delivery opening, means for feeding the fuel to the opening, a plurality of rotatable pivotally-supported blades within the opening for forcing the fuel therethrough, and means for rotating the blades, the free edge of the blades being split and the portions of the edge between the splits being deflected beyond both faces thereof to form spaced parallel wings extending in an oblique direction with relation to and across the body of the blade to deflect the fuel, the wings on each alternate blade being disposed in the opposite direction and adapted to pass over the edge of the bottom of the hopper.
24. A device of the class described containing a hopper for the fuel having a delivery opening, means for feeding the fuel to the opening, a plurality of rotatable pivotally-supported blades within the opening for forcing the fuel therethrough, and means for rotating the blades, the free edge of the blades being split and the portions of the edge between the splits being deflected beyond both faces thereof to form spaced parallel wings extending in an oblique direction

with relation to and across the body of the blade to deflect the fuel, said blades being provided with perforations above the wings. 30

25. A device of the class described containing a hopper having a delivery opening the bottom of which is provided with an irregular front edge, means for feeding the fuel to the opening, a plurality of rotatable pivotally-supported blades within the delivery opening for forcing the fuel therethrough, obliquely disposed spaced wings operatively related to the free edge of the blades and extending transversely with relation to said edge, said wings coöperating with the said irregular front edge of the discharge opening to distribute the fuel when the blades are rotated, and means for rotating the blades. 40

In testimony whereof I have signed my name to this specification, in the presence of two subscribing witnesses, on this 27th day of February A. D. 1907.

GEORGE L. SWIFT.
